(57) **CLAIM**

The ornamental design for a wireless earphones with charging case, as shown and described.

DESCRIPTION

FIG. 1 is a perspective view of the wireless earphones with charging case, with the wireless earphones shown separately from the charging case in order to illustrate details not otherwise visible.

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the wireless earphones with charging case, shown in an open configuration with the charging case shown separately from the wireless earphones in order to illustrate details not otherwise visible.

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

(Continued)

FIG. 15 is a top plan view thereof;
 FIG. 16 is a bottom plan view thereof;
 FIG. 17 is a perspective view of the wireless earphones with charging case, shown in use with the earphones received in the charging case; and,
 FIG. 18 is a perspective view of the wireless earphones with charging case, shown in a closed configuration.
 The broken lines in the drawings depict portions of the wireless earphones with charging case that form no part of the claimed design.
